H. ERVIEN.
DOOR CURTAIN FOR VEHICLES.
APPLICATION FILED DEO. 28, 1911.

1,047,017.

Patented Dec. 10, 1912.

Fig. 1.

UNITED STATES PATENT OFFICE.

HORACE ERVIEN, OF OGONTZ, PENNSYLVANIA.

DOOR-CURTAIN FOR VEHICLES.

1,047,017.

Specification of Letters Patent. Patented Dec. 10, 1912.

Application filed December 28, 1911. Serial No. 668,382.

To all whom it may concern:

Be it known that I, HORACE ERVIEN, a citizen of the United States, residing in Ogontz, county of Montgomery, State of Pennsylvania, have invented certain Improvements in Door-Curtains for Vehicles, of which the following is a specification.

One object of my invention is to provide means whereby the curtain of an automobile or other vehicle will move with the door when the said door is opened or closed.

A further object of the invention is to make the curtain readily detachable, so that it can be rolled into a small compass.

In the accompanying drawings:—Figure 1, is a side view of an automobile illustrating my invention; Fig. 2, is a sectional plan view on the line 2—2, Fig. 1, showing the door closed; Fig. 3, is a similar view to Fig. 2, showing the door partly opened; Fig. 4, is an enlarged sectional view on the line 4—4, Fig. 1; Fig. 5, is a detached perspective view of the curtain; Fig. 6, is a perspective view illustrating a portion of the door, 25 showing the sockets; Fig. 7, is a detached perspective view of the flexible metallic top bar, which supports the upper edge of the curtain; Fig. 8, is a perspective view of the detachable upright; Fig. 9, is an enlarged 30 perspective view of the socket for the reception of the said upright and Fig. 10 is an enlarged sectional view taken on the line 5—5, Fig. 1 showing the manner in which the upper portion of the door curtain is secured.

A is the body of the vehicle, an automobile in the present instance.

B is the door mounted on hinges b, b; these hinges may be at the rear end, as indicated in Fig. 1, or may be mounted at the forward end of the door, depending upon the type of the vehicle.

c is a socket tapered as shown and secured, in the present instance, to the inner side of the door at the forward end, Fig. 6, and D is an upright having a tapered end d adapted to the socket. This upright is shaped as clearly shown in Fig. 4, to conform to the shape of the bows of the top.

E is a curtain, and permanently secured to the upper edge of the curtain is a metallic strip F. This strip is made flexible at the inner end and is preferably made from a piece of thin metal bent to form a loop f, and the two portions of the strip are secured at intervals by fastenings f'. This

metal strip is mounted in a pocket e extending along the upper edge of the curtain E and the loop f is in line with a vertical pocket e' at the outer edge of the curtain. 60 This last mentioned pocket is for the reception of the upright D. The flexible section f' of the strip F forms what I term a flexible hinge, and this hinge is located preferably in line with the pivot hinges of the door 65 so that it will yield when the door turns on its hinges, as illustrated in Figs. 2 and 3.

In the lower edge of the curtain are eyes g, g adapted to buttons h on the door, and the inner upper corner of the curtain is provided with a button or eye i adapted to an eye or button i' on the top A', and, in some instances, one or more buttons may be provided along the inner edge of the curtain E by which it is attached to the back curtain 75 N, if found desirable..

At the front edge of the door opening is a detachable bar M having a socket m on the frame A, and this upright supports the rear edge of the forward curtain P.

The rear end of the curtain extends only to the rear end of the door, and the rear curtain N underlaps the curtain E, as shown, at n'. The rear end of the forward curtain P has a narrow flap p which extends over 85 the front edge of the curtain E, and I preferably extend the lower edge a of the top over the upper edge of the curtain so as to prevent rain gaining access through the space between the curtain and the top. 90

By making the detachable door curtain in the manner described, the curtain opens with the door so that a person can enter or leave the vehicle without detaching the curtain or a portion of it as is now customary. The 95 curtain, owing to the flexible upper strip, yields at the inner edge when the door is opened, as shown in Fig. 3, thus keeping the inner joint tight. The rigid portion of the upper strip F will hold the curtain in proper 100 position.

In a door of the construction shown in the accompanying drawings, in which the roof or top covering A' projects beyond the plane of the door at its hinges, the line of bend of the door curtain will, of course, not be on a straight line but will follow the general contour of the curtain at this point; however, in many vehicles, the hinges and the door are substantially in the same plane, 110 and, in this instance, the line of bend of the door curtain will be substantially straight.

It will thus be understood that my invention may be used on vehicles of any known shape.

When it is not necessary to use the curtain it can be quickly removed and rolled upon the upper strip F and the upright D may be rolled with it if desired.

I claim:

1. The combination in a vehicle, of a top; 10 a body portion; a doorway; a door pivoted to the body portion and closing the lower portion of the doorway; an upright secured to the door; a flexible horizontal hinge strip connected at one end to the upright; said hinge strip being in line with the pivot of the door; with a curtain extension secured to the flexible hinge strip at its upper edge and to the door at its lower edge so that when the door is open the flexible hinge strip 15 will accommodate itself to the movement of the door on the pivoted hinge.
2. The combination in a vehicle in which the top is wider than the body, of a door hinged to the body by pivot hinges and closing part of the doorway; an upright detachably secured to the outer end of the door; a flexible hinge strip attached at one end to the upright and at the other end to the top of the body portion of the vehicle; 20 with a curtain secured to the flexible hinge strip at its upper end and to the door at its lower edge; the upper edge of the curtain projecting beyond the door; the parts being so arranged that when the door is turned 25 on its pivot, the flexible hinge strip will yield and will accommodate itself to the movement of the door so that the curtain will be carried, with the door, to permit of ingress and egress through the doorway.
3. The combination in a vehicle having a 30 doorway therein; a top; a door closing part of the doorway and hinges connecting the door with the body; an upright at the outer edge of the door and detachably secured thereto; with a horizontally arranged flexible strip attached at one end to the upright and attached to the top at the inner end; said strip having a flexible hinge portion 35 near the point where it is attached to the top; with a curtain secured to the flexible

strip at its upper edge and to the door at its lower edge so that when the door is open, the curtain will move with it; said movement flexing the hinge strip near the top of the vehicle.

55

4. The combination in a vehicle body, of a movable top thereon; a doorway; a pivoted door arranged to close the lower portion of the doorway; an upright detachably mounted at the upper portion of the door 60 and extending up to the top of the doorway; a flexible strip having a socket adapted to receive the end of the upright and to extend back to a point near the vertical line of the hinge of the door; means for attaching said strip to the top; a curtain having a horizontal socket adapted to receive the flexible strip and a vertical socket adapted to receive the upright; with means for attaching the curtain to the door; the parts 65 being so arranged that, upon the opening of the door, the flexible portion of the metallic strip and the curtain will be flexed.

65

5. The combination in a vehicle, of a body portion; a movable top; said vehicle having 70 a doorway partly in the body portion and partly in the top; a door adapted to the body and closing the lower portion of the doorway; a tapered socket in the outer edge of the door; an upright having a tapered 75 portion adapted to the socket; a flexible metallic strip bent to form a socket; said socket being adapted to receive the upper end of the upright; a curtain having a horizontal pocket adapted to receive the metallic strip; 80 a vertical pocket near one edge adapted to receive the upright; said flexible strip and curtain each having an eye near the inner edge; a fastening on the top adapted to pass through the said eyes; the curtain being attached, at its lower edge, to the door so that when the door is open the curtain and the metallic strip will be flexed.

85

In testimony whereof, I have signed my name to this specification, in the presence of 90 two subscribing witnesses.

90

HORACE ERVIEN.
